UNITED STATES PATENT OFFICE.

MOSES G. COOK, OF LYNN, MASSACHUSETTS.

WEIGHING-SCALE.

SPECIFICATION forming part of Letters Patent No. 327,530, dated October 6, 1885.

Application filed May 2, 1884. Serial No. 130,162. (No model.)

To all whom it may concern:

Be it known that I, MOSES G. COOK, of Lynn, county of Essex, State of Massachusetts, have invented an Improvement in Seales, of 5 which the following description, in connection with the accompanying drawings, is a specification, like letters on the drawings representing like parts.

This invention relates to certain improvements in Letters Patent No. 267,776, granted to me, and to Jos. N. Smith, as the assignee of one-half interest, on the 21st day of November, 1882.

As fully set forth in that patent, to which 15 reference is made for a full and detailed description of all the parts of the scale, the weights, which may be successively lifted by the inclined weight-lifting device whenever an article is to be weighed, are provided with 20 lateral projections or holding-lugs, which rest in notches in the weight-supporting bars, and are also caught in notches in the inclined weight-lifting device when the latter is raised by means of the weight placed in the proper 25 weighing-pan.

Other than the notches in the weight supporting and lifting devices no means are provided in said patent to prevent displacement of the weights by reason of sudden movement 30 or jars imparted to the scale, and in usage I have often seen the necessity for providing against such displacement.

My present invention has for its object to 35 prevent the displacement of the weights by reason of any sudden movement or jars imparted to the scale, and to insure their constant engagement with the proper notches of either the weight-supporting bars or weight-lifting device as the scale is at rest or in action.

40 My invention has for its further object to simplify the connection and operation of the parts which convey motion from the scale-beam to the pointer, which operates in connection with the graduated dial.

45 The nature of these improvements is fully set forth in the following description, and particularly pointed out in the claim.

Figure 1 is a front elevation of a scale containing my invention; Fig. 2, an end view 50 thereof; Fig. 3, a section on line $y-y$ of Fig. 2, to more clearly show the weight-actuating parts and the rod which completes the con-

nnection of the pointer with the scale-beam; and Fig. 4, a detail illustrating the pointer-actuating mechanism.

The scale-beam a , pivoted on the standards b , having the pans $c f$, standards $d g$, radius-bars $e i$, and frame h and guide p , are of the construction described in the patent referred to.

In this instance the movable frame h , pivoted, as shown, to the lower end of the standard g , is provided with two parallel weight-lifting plates, j , preferably of the form shown in Fig. 2—that is to say, with horizontal or straight upper surfaces and inclined lower 65 surfaces, and provided with vertical slots j' of gradually-increasing length from end to end of the plates, all of said slots, however, being of substantially the same width.

A line parallel with the horizontal upper 70 edges of the plates will intersect the upper terminals or ends of the slots, and a second line drawn at an acute angle to the first line but parallel with the lower edges or bottoms of said plates will intersect the lower terminals of said slots, and consequently said slots will vary in length. The lower terminals of the slots will be successively brought to a given level as the frame is raised by the depression of the platform e at the other end of the scale. 75

The stationary frame-work, rigidly secured to the base, as shown, is provided with stationary weight-supporting bars k , notched at their upper edges to correspond in position and manner with the slots in the plates j .

In the normal position of the scale the inclined bottoms of the plates j are maintained wholly below the upper surface of the weight-supporting bars k , with the lower terminal of the shortest slot of said plates, which corresponds to the "highest notch" mentioned in the patent referred to, on a level with or just beneath the corresponding notch at the left of the said bars, viewing Fig. 2.

The weights m are of the construction set 95 forth in the patent referred to, and their projections n pass through the slots j' in the weight-lifting plates j , and rest in the notches of the weight-supporting bars k . By this construction the projections n cannot escape from the slots in the plates j , and whenever, by the operation of the apparatus, the said projections are lifted from the notched bars k and then lowered they will always be returned to 100

their respective notches; besides, whatever the jar or sudden movement that may be imparted to the scale, the slotted plates *j* will constantly retain the weights in proper position and cause them to be returned to their respective notches in the supporting-bars, as stated.

The weights are provided with notches *o*, as shown in dotted lines, Fig. 3, which, in co-operation with the guide *p*, mounted on the frame-work, serves to place them in proper position between the supporting-bars *k* as they are deposited thereon upon the depression of the slotted plates *j*.

15 A depending connecting-rod, *r*, is pivoted to the scale-beam *a* at a point between its central pivots, 2, and the standard *g*, and the lower end of said rod is attached to a pin, *r'*, secured to the pointer-actuating lever *s* and 20 projecting through a slot in the back of the dial-case *S*.

The pointer-actuating lever *s* is pivoted at one end within the dial-case, as at 4, (see Fig. 4,) and is provided at its opposite end with a 25 number of teeth, *s'*, which engage the pinion *x* on the arbor *t*, to operate the pointer *u*, which co-operates with a dial, *v*, having the series of concentric graduated circles, the said 30 pointer thus receiving a movement corresponding with the movement of the scale-beam.

The movement of the pointer with relation to the dial and other parts of the scale is fully described in the patent mentioned herein, and 35 needs no further description.

The pocket 16 for the lever *s* is secured within the case *S*, with one end supporting the arbor *t* and the other end the pivot 4, as well as being intended to prevent lateral swing or 40 play of the lever *s*, as will be clearly understood upon inspection of Fig. 4 of the drawings.

It will be noticed that the depending rod is connected with the pointer-actuating lever 45 between the pivotal and toothed ends of the same.

The dial-case is mounted on the base of the scales.

In the present instance I employ but six- 50 teen weights, and make the outer circle of the

dial in half-ounce divisions up to eight ounces, instead of to sixteen, as heretofore; and, further, change the letter - postage circle from three cents per half-ounce to two cents per half-ounce, to conform to the present rates for letter-postage.

Providing the weight-lifting plates with slots, as shown at *j'*, to receive and hold the projections of the weights renders it impossible for the weight to get back into any other 60 notch of the bar *k*, except the one from which it was lifted, no matter how carelessly the scale is handled in weighing.

The V-shaped pivot-bearings 2 (see Figs. 2 and 3) of the scale-beam *a*, projecting from the 65 sides of the beam and resting in the tops of the standards *b*, are covered by caps *a'*, (see Fig. 1,) attached to the standards *b* by screws 8, and each of the said caps *a'* is provided with an adjusting-screw, *a''*, bearing against the ends 70 of the pivots 2, so that by movement thereof the scale-beam may be moved laterally, the ends of the said screws *a''* also acting against the ends of the pivot-bearings 2 to form stops for the same and prevent any reciprocation or 75 lateral sliding of the beam as the scale is being used.

I claim—

In a scale or weighing apparatus, the combination, with the scale-beam having the pivoted frame *h*, provided with weight-lifting plates having slots of increasing length in succession, with the upper slot terminals in line with one another, of horizontal weight-supporting bars secured in a weight-receptacle, 80 and having notches corresponding in number and position with the slots in the lifting-plates, and a series of weights provided with projections passing through the slots in the lifting-plates and resting in the notches of the supporting-bars and adapted to be lifted therefrom by the slotted plates in the movement of the scale-beam, substantially as described.

In testimony whereof I have signed my name to this specification in the presence of 95 two subscribing witnesses.

MOSES G. COOK.
